GERRET REKERS, OF ROCHESTER, NEW YORK, ASSIGNOR TO GENERAL RAILWAY SIGNAL COMPANY, OF GATES, NEW YORK, A CORPORATION OF NEW YORK.

SEMAPHORE-SIGNAL MECHANISM.

1,297,970.

Specification of Letters Patent. Patented Mar. 18, 1919.

Continuation in part of application Serial No. 762,570, filed April 21, 1913. This application filed July 20, 1916. Serial No. 110,313.

To all whom it may concern:

Be it known that I, GERRET REKERS, a citizen of the United States, and a resident of the city of Rochester, in the county of Monroe and State of New York, have invented a new and useful Semaphore-Signal Mechanism, of which the following is a specification.

This invention relates to that class of devices which are employed in railway signaling and which are ordinarily termed semaphore operating mechanisms.

This application is a continuation of my prior application Serial No. 762,570 filed April 21, 1913, which has matured into Patent No. 1,272,099, July 9, 1918.

The primary object of this invention is to design and construct a mechanism for operating a semaphore, such that the semaphore will be moved from a biased to an operated position by the operation of any well known form of rotary motor, and in which the motor will act to bring the semaphore to rest without objectionable shock or jar in a biased position when the semaphore moves from an operated position to said biased position in response to its bias.

Other objects and advantages will appear as the description of the invention progresses, and the novel features of the invention will be particularly pointed out in the appended claims.

In describing the invention in detail, reference is had to the accompanying drawing, wherein I have illustrated a preferred physical embodiment of my invention, and wherein like characters of reference designate corresponding parts throughout the several views, and in which:

Figure 1 is a partly diagrammatic view showing the parts of a semaphore operating mechanism embodying the invention; Fig. 2 is an enlarged vertical section through the circuit controller shown in Fig. 1, said section being taken on the line 2-2 in Fig. 1 and looking in the direction indicated by the arrow *a*, and shows the slip contact in the position it assumes when the semaphore is moving toward an operated position; Fig. 3 is an enlarged vertical section similar to Fig. 2 and shows the position of the slip contact when the semaphore is moving from an operated position toward a biased position; Fig. 4 is an enlarged detail view show-

ing particularly the slip contact; and Fig. 5 is a diagrammatic view of the parts of the semaphore operating mechanism and shows an arrangement of operating circuits suitable for controlling this mechanism.

Referring to Fig. 1 of the accompanying drawing, the improvement embodying this invention is illustrated as incorporated with a well known type of semaphore operating mechanism which is clearly shown and described in the patent to W. K. Howe, 1,056,992, March 25, 1913. The numeral 1 designates the main casing of the semaphore operating mechanism which is formed with an opening at its rear end which may be closed by a hinged cover 2. Within the main casing 1 there is supported a motor casing 3 which is also provided with a cover 4, and in which is supported an electric motor of suitable construction for operating the semaphore, the motor shown being of the direct current type having field coils 5, an armature 6, a commutator 7 and brushes 8.

The armature shaft 9 of the operating motor is provided with suitable electrically controlled means, commonly termed a "hold clear" device, which serves to hold said armature shaft against movement in one direction so as to retain the semaphore in an operated position. The "hold clear" device illustrated in Fig. 1 is of the type shown and described in the patent to W. K. Howe, 985,677, Feb. 28, 1911, and in general comprises a ratchet wheel 10, an arm 11 carrying a detent adapted to coöperate with said ratchet wheel, and an electro-magnet 12 for moving said arm 11 into position to produce coöperation of the detent carried by said arm with said ratchet wheel, the arm 11 being returned to its normal position when the electro-magnet 12 is deenergized by means of the weight of the movable core of the electro-magnet 12, all as shown and described in detail in said Patent 985,677.

Fastened to the end of the armature shaft 9 of the operating motor which projects through the front end of the motor casing 3, is a pinion 14 which meshes with a gear 15 loosely mounted on a shaft 16 to which the semaphore blade 60 is attached. Integral with or secured to the gear 15 is a pinion 17 which meshes with a gear 18 journaled on a shaft 19 secured in the main casing 1; and also journaled on the shaft 19

is a pinion 20 which is connected to the gear 18, preferably by means of a ratchet-and-pawl mechanism (not shown) as shown and described in the Patent 1,056,992, above mentioned, the pinion 20 being in mesh with a segmental gear 21 fixed to the semaphore shaft 16.

In the main casing 1 of the semaphore operating mechanism and disposed above the 10 motor casing 3 is a circuit controller, designated generally by the reference character K, which comprises a supporting plate 47 which is fastened to the main casing 1 by bolts 46, (see Fig. 1) and from which project arms 48 and 49 connected at their outer ends by means of a web or cross brace 50 and at their inner ends by means of the plate 47. The arms 48 and 49 support blocks 51 of insulating material which support 20 adjustable contact fingers 52 by means of binding posts 53. A shaft 22 extends through the supporting plate 47 and the cross brace 50, and fixed to the shaft 22 is a segmental gear 23 which meshes with a 25 similar segmental gear 24 fastened to the semaphore shaft 16. Between the supporting plate 47 and the cross brace 50 is disposed a drum 54 of insulating material rigidly attached to the shaft 22 by means of a 30 screw 55. The drum of insulating material 54 carries metallic strips 106 which are positioned so as to lie in the path of the contact fingers 52. In the accompanying drawing all of the contact fingers 52 have been 35 shown on one side of the circuit controller K for convenience, but it is to be understood that some of these contact fingers may be and preferably are on the opposite side of the circuit controller.

40 The circuit controller K above described is substantially identical with that shown and described in the application of William S. Henry Serial No. 742,800, filed Jan. 18, 1913, but has, however, one feature not 45 shown in the above mentioned application, which is known as a slip contact and which consists of a spring arm 56 which is attached to the lower insulating block 51 in the same manner as the contact fingers 52 are attached 50 and which bears at the outer end a cup-shaped member 57 in which one end of a pin 58 is loosely positioned. The other end of the pin 58 is loosely positioned in a cavity formed in a member 59. The member 59 is 55 formed with an arc-shaped face which bears against the insulating drum 54, a shallow circumferential groove being preferably formed in said insulating drum to guide the member 59. The rotation of the drum 54 in 60 the direction of the arrow P, Fig. 3, causes a downward movement of the member 59 into the position shown in Fig. 2; but a movement of the insulating drum 54 in a direction opposite to the arrow P causes the 65 member 59 to move upwardly and to con-

tact with a contact finger, as 76, positioned in line with it and supported by the upper insulating block 51, as shown in Fig. 3.

In Fig. 5 I have shown schematically the circuit controller K, the electro-magnet 12 70 for operating the "hold clear" device, the operating motor and the gearing connecting the armature of said motor with the semaphore 75 60, together with an arrangement of operating circuits suitable for controlling the operation of the semaphore according to this invention.

Referring to Fig. 5, 62 designates a source of current; 63 a switch arm which may be moved from the position shown in full lines 80 to the dotted line position; and 64, another switch arm which may be moved from the full line position to the dotted line position.

The parts are shown in Fig. 5 in the positions which they assume after the semaphore 85 has been operated to its vertical or 90° operated position, and with the parts in this position shown in Fig. 5, current will flow as follows: positive terminal of the battery 62, wire 65, switch arm 63, wires 66 and 67, 90 switch arm 64, wires 68 and 69 to the contact finger 70, metallic strip 71, contact finger 72, wires 73 and 74, to the coil of the electro-magnet 12, and then from said electro-magnet along wire 107 to wire 75, 95 and back to the negative terminal of the battery 62. Current flowing in the above traced path will energize the electro-magnet 12 and will operate the "hold clear" device 100 so as to hold the semaphore 60 in its operated position.

If the switch arm 64 is moved to the dotted line position, the flow of current through the electro-magnet 12 will be interrupted, and the "hold clear" device being released, the 105 semaphore 60 in response to its bias will rotate clockwise, as viewed in Fig. 5, toward its diagonal or caution position. This clockwise rotation of the semaphore 60 and the semaphore shaft 16 will cause a counter-clockwise rotation of the drum 54 by means of the segmental gears 23 and 24, and will cause the member 59 of the slip contact to contact with the contact finger 76, so that when the drum 54 has been rotated sufficiently for the strip 77 to make contact between the contact fingers 78 and 79, a circuit will be formed in which current flows as follows: positive terminal of the battery 62, wire 65, switch arm 63, wires 66 and 80, 110 contact finger 78, strip 77, contact finger 79, wires 81 and 82, contact finger 76, member 59, contact finger 83, wires 84 and 85, through the armature and field coils of the operating motor and wires 108 and 75 back 115 to the negative terminal of the battery 62. Current flowing in the above traced path would cause an energization of the operating motor so that it would tend to move the semaphore 60 toward its operated position, 120 130

- but the action is merely momentary because the strip 77 is so adjusted in its position on the drum 54 that it makes contact between strip 78 and 79 just before the semaphore 60 reaches the diagonal or caution position and breaks contact with the strip 79 immediately thereafter, so that the effect is merely that of a dash pot to bring the semaphore 60 to rest at the caution position.
- 10 When the semaphore 60 reaches the caution position a circuit is formed in which current flows as follows: positive terminal of the battery 62, wire 65, switch arm 63, wires 66, 86 and 92, contact finger 93, strip 94 caused to bridge contact fingers 93 and 95 by the counterclockwise rotation of the drum 54 caused by the fall of the semaphore 60, contact finger 95, wires 96 and 74, winding of the electro-magnet 12 and wires 107 and 75 back to the negative terminal of the battery 62. Current flowing in the above traced path will energize the electro-magnet 12 operating the "hold clear" device, so that the semaphore 60 will be held in the caution position.
- If the switch arm 63 is moved to the dotted line position, the circuit through which current flows to hold the semaphore 60 in the caution position will be broken, and consequently, the semaphore by reason of its bias will move to the horizontal or danger position and in so doing will again rotate the drum 54 counterclockwise, causing the member 59 of the slip contact to contact with the contact finger 76, if it is not already in contact therewith, and thus forming an electrical dash pot circuit in which current flows as follows: positive terminal of the battery 62, wire 65, switch arm 63 in the dotted line position, wire 97, contact finger 98, metallic strip 99, contact finger 100, wires 101 and 82, contact finger 76, member 59, contact finger 83, wires 84 and 85 through the armature and field coils of the operating motor and wires 108 and 75 back to the negative terminal of the battery 62. The metallic strip 99 would only make momentary connection between the contact fingers 98 and 100, and when the semaphore 60 has arrived at its full biased horizontal position, will have broken contact between the two fingers 98 and 100, so that the effect will be merely that of a dash pot acting temporarily to restrain a too violent motion of the semaphore 60 to the biased position.
- The return of the semaphore 60 to the horizontal position will cause the metallic strip 89 to bridge the contact fingers 88 and 90 so that, if the switch arm 63 were again moved to the full line position, current would flow in the following path: positive terminal of the battery 62, wire 65, switch arm 63, wires 66, 86 and 87, contact finger 88, metallic strip 89, contact finger 90, wires 91 and 85 through the armature and field coils of the operating motor and wires 108 and 75 back to the negative terminal of the battery 62. Current flowing in the above traced path will cause the armature of the operating motor to rotate in a clockwise direction, as viewed in Fig. 5, to move the semaphore 60 to the caution position, at which position the metallic strip 89 will have moved from contact with the contact finger 88 thus breaking the operating circuit just traced, but at the same time, the contact strip 94 will have moved so as to bridge the contact fingers 93 and 95 so that the holding circuit for the caution position of the semaphore as heretofore traced will be formed.
- If after the semaphore 60 has arrived in the caution position, the switch arm 64 is moved to the full line position and the switch arm 63 is still in the full line position, then as the metallic strip 61 moves so as to bridge contact fingers 102 and 103 by the movement of the semaphore to the caution position, current will flow in a path which may be traced as follows: positive terminal of the battery 62, wire 65, switch arm 63, wires 66 and 67, switch arm 64, wires 68 and 104, contact finger 102, metallic strip 61, contact finger 103, wires 105 and 85 through the armature and field coils of the operating motor, and wires 108 and 75 back to the negative terminal of the battery 62. Current flowing in the above traced path will cause the semaphore 60 to be moved to the vertical or 90° operated position and the drum 54 moved so that the metallic strip 71 makes contact between the contact finger 70 and the contact finger 72, so that the holding circuit for the vertical or 90° operated position of the semaphore 60 as heretofore traced would be formed.
- From the foregoing it can be seen that there is provided according to this invention a semaphore operating mechanism in which the semaphore blade is brought to rest without shock or jar in either of its biased positions by the action of the operating motor whenever the semaphore blade moves from an operated position to a biased position. While the means employed according to this invention for regulating the movement of a semaphore from an operated position to a biased position may be used in connection with any type of semaphore operating mechanism, whether operated by a direct current motor or by an alternating current motor, this means is especially applicable to the type of semaphore operating mechanism shown and described in my co-pending application Serial No. 110,312 filed July 20th, 1916, since in the semaphore operating mechanism described in said application the arc of movement of the armature of the motor when the semaphore moves from its vertical to the horizontal position is the same as the arc of movement of the

4
semaphore, namely, only 90°, and this small movement of the armature of the motor would not be sufficient to generate sufficient current to effectually retard the movement 5 of the semaphore toward its horizontal position by shortcircuiting the operating motor according to the method heretofore employed.

Although I have particularly described 10 the construction of one physical embodiment of my invention, and explained the operation and principle thereof; nevertheless, I desire to have it understood that the form selected is merely illustrative, but does 15 not exhaust the possible physical embodiments of the idea of means underlying my invention.

What I claim as new and desire to secure by Letters Patent of the United States, is:

20 1. In combination, a signal biased to one position of indication, a motor operatively connected at all times with the signal to move the latter to another position and to move with the signal while the latter is returning 25 in response to its bias, and means for energizing the motor to retard the signal during a portion of said return movement.

2. In combination, a signal biased to danger 30 position, a motor operatively connected at all times with the signal to move it to caution and clear positions and to move with the signal while the latter is returning in response to its bias, and means for energizing said motor to retard the signal while returning from its clear to its caution position.

3. In combination, a signal biased to danger 40 position of indication, a motor operatively connected with the signal to move it to caution and clear positions and to move with the signal while the latter is returning toward its biased position, means for holding the signal in the caution and clear positions, and means for energizing the motor to retard the signal while returning from the clear position toward the caution position in response to its bias, and for de- 45 energizing the motor after the signal has reached the caution position, and for then energizing the said holding means.

4. In a semaphore operating mechanism, in combination: a semaphore; oscillatable circuit controlling means connected to the 55 semaphore; a member coöperating with said means and adapted to be moved by friction; and other circuit controlling means arranged to be engaged by said member when it is moved in one direction.

60 5. In combination, a signal biased to danger position of indication, an electric motor operatively connected with the signal to move it to caution and clear positions and to move with the signal while the latter is 65 returning toward its danger position, a

source of operating current for the motor, circuits and circuit controlling devices for controlling said signal, a snubbing circuit including said source for energizing the motor, a circuit controller for controlling 70 said circuit, frictional means interposed between the signal and said circuit controller tending to open said circuit controller while the signal is moving away from its biased position and to close the circuit controller 75 while the signal is moving toward its biased position, and a second circuit controller operated by the signal for the control of said circuit, said second circuit controller being closed only during a portion of the movement of the signal between its clear and caution positions.

6. In a signal operating mechanism, in combination: a pivoted arm having a set position and a biased position; an electric 85 motor operatively connected to said arm for moving said arm to its set position; circuit and circuit controlling devices for controlling the movements of said arm; a circuit controller governed by the movement of said 90 arm and selectively responsive to the direction of movement thereof, said circuit controller being closed when said arm moves to its biased position and being opened when said arm moves to its set position; another circuit controller governed by said 95 arm and closed during a portion of the movement of said arm near its biased position; and a snubbing circuit for said motor including in series said circuit controllers. 100

7. In a signal operating mechanism, in combination: a pivoted arm having a biased position and two operated positions; an electric motor operatively connected to said arm for moving said arm to its operated 105 positions; circuit and circuit controlling devices for controlling the movements of said arm; a circuit controller governed by the movement of said arm and selectively responsive to the direction of movement thereof, said circuit controller being closed when said arm moves toward its biased position and being opened when said arm moves toward its operated positions; two other circuit controllers governed by said arm, one 110 being closed during a portion of the movement thereof near its biased position, and the other near its intermediate operated position; and snubbing circuits for said motor each including in series said first-mentioned 115 circuit controller and one of said other circuit controllers.

8. In a signal operating mechanism, in combination: a pivoted arm having a set position and a biased position; an electric 125 motor operatively connected to said arm for moving said arm to its set position; circuit and circuit controlling devices for controlling the movement of said arm, a circuit controller governed by said arm and 130

- selectively responsive to the direction of movement thereof; said circuit controller being closed when said arm moves toward its biased position and being opened when 5 said arm moves toward its set position; another circuit controller governed by said arm and closed during a portion of the movement thereof near its biased position; a snubbing circuit for said motor including 10 in series said circuit controllers; electromagnetic means for holding said arm in its set position; a third circuit controller governed by said arm and closed when said arm is in its set position; and a controlling 15 circuit for said electromagnetic means including said third circuit controller.
9. In an electric signal mechanism, in combination: an oscillatable arm having a set position and a normal biased position; 20 an electric motor; means connecting the electric motor with the arm, whereby the operation of the motor causes a set position of said arm and the oscillation of the arm due to its bias causes an operation of the motor; a 25 drum connected to and operable in unison with the arm; a member formed with a curved face bearing against the periphery of the drum; means for supporting said member in frictional contact with the drum and 30 for allowing said member to be moved a limited extent in opposite directions by the movement of the drum; a fixed member arranged in the path of movement of said member and adapted to form electrical contact therewith which is closed during the 35 return movement of said arm in response to its bias, but is opened during the movement of said drum caused by said motor; a circuit controller governed by said arm and closed 40 during a portion of the movement of said arm near its biased position; and a snubbing circuit for said motor including in series said first-mentioned member, said fixed member and said circuit controller.
- 45 10. In an electric signal mechanism, in combination; an oscillatable drum connected to the semaphore; a member coöperating with the drum and adapted to be moved by friction; and a fixed contact arranged to be 50 engaged by said member when it is moved in one direction.
11. A semaphore signal operating mechanism, comprising a semaphore; an oscillatable drum operatively connected to said 55 semaphore; a slip contact member having a curved face shaped to bear against the surface of said drum; a spring arm fixed at one end; means loosely connecting said spring arm and said slip contact member and permitting a slight movement of said slip contact member with reference to said spring arm; and a contact finger disposed in the path of movement of said slip contact finger.
- 60 12. In a semaphore signal operating mechanism, in combination: a semaphore; an os-

cillatable drum operatively connected to said semaphore; a friction member having one face thereof shaped to bear against the surface of said drum and having a cavity formed in its opposite face; a spring arm 70 fixed at one end and carrying at its other end a member having a cavity therein; a pin loosely supported in said cavities and limiting the movement of said friction member relative to said spring arm; and an adjustable contact finger disposed in the path of movement of said friction member. 75

13. In a semaphore signal operating mechanism comprising a semaphore and an operating motor connected thereto to move 80 with the semaphore when it is moving toward its biased position, in combination with a snubbing circuit for the motor, a circuit controlling means, included in said circuit, and means including a frictional device for operating said circuit controlling means when the semaphore moves toward a biased position.

14. In a semaphore signal operating mechanism in combination: a semaphore; an electric motor operatively connected with said semaphore to move it to an operated position and to move with the semaphore while the latter is returning in response to its bias; circuit controlling means governed by the 90 movements of said semaphore; frictional means interposed between said semaphore and said circuit controlling means; and two circuits in parallel through the motor, each of said circuits being governed by said 95 circuit controlling means, one for energizing the motor to move the semaphore in one direction to an operated position and the other of said circuits, including in series said frictional means, for energizing the motor to 100 retard the movement of said semaphore when it moves from an operated position in response to its bias. 105

15. In an electric signal mechanism, in combination: a semaphore; an oscillatable 110 drum operatively connected to the semaphore; a member having a curved face shaped to bear against the periphery of said drum and adapted to be moved by friction; a resilient support for said member; means 115 loosely connecting said member to its support and for limiting the movement of said member in either direction; and a fixed contact arranged to be engaged by said member when it is moved in one direction. 120

16. In combination, a signal biased to one position of indication and capable of being moved against its bias to another position of indication, means for retarding the signal during its movement toward its biased position, a circuit for controlling said means, a circuit controller for controlling said circuit, and frictional means interposed between the signal and the circuit controller for closing the latter while the signal is moving toward 125 130

6
its biased position and for opening the circuit controller while the signal is moving away from its biased position.

17. In a semaphore operating mechanism, 5 in combination: a semaphore; a movable member operatively connected with the semaphore by a frictional slip connection

and adapted to be moved in one direction or the other in accordance with the direction of movement of the semaphore; means limiting the movement of said member; and circuit controlling means operated by said member at one of its extreme positions.

GERRET REKERS.
